Inventor:
Adam L. Kaufman

By Attorney:

UNITED STATES PATENT OFFICE.

ADAM W. KAUFMAN, OF MILWAUKEE, WISCONSIN.

TIMER.

Application filed June 17, 1922. Serial No. 568,980.

To all whom it may concern:

Be it known that I, ADAM W. KAUFMAN, a citizen of the United States, and resident of Milwaukee, in the county of Milwaukee, 5 and State of Wisconsin, have invented certain new and useful Improvements in Timers; and I do hereby declare that the following is a full, clear, and exact description thereof.

10 This invention pertains to ignition timers for internal combustion engines.

The primary object of the invention resides in the reduction of wear upon the contact members by the provision of a rotor, 15 yieldable longitudinally of the timer shaft, whereby longitudinal movement of the shaft is compensated for and a uniform minimum frictional engagement, between the rotor and contacts is maintained at all times.

20 A more specific object resides in the provision of a sleeve adapted to be attached to a conventional type of timer shaft without necessitating alterations in the shaft or present mode of attaching the rotor; and in the 25 arrangement of assembling the rotor on the sleeve, whereby an inexpensive and compact structure of the above character is obtained.

With the foregoing and other objects in view, which will be more apparent as the 30 description proceeds, the invention consists in what is herein shown and described and more particularly pointed out and defined by the appended claims, it being understood that various modifications of the 35 structural details are within the scope of the invention.

In the drawings,

Figure 1 is a vertical sectional view of a timer constructed in accordance with the 40 present invention.

Figure 2 is a detail sectional view taken on the line 2-2 of Figure 3, and

45 Figure 3 is a vertical sectional view thru the rotor, as indicated by the line 3-3 of Figure 2.

Referring now more particularly to the accompanying drawings, the numeral 1 designates a rotary timer shaft provided with a reduced end 2, which forms the shoulder 3. Fitted over the reduced portion is a sleeve 4, reduced at one end to provide a shoulder 5, the reduced end of the sleeve being provided on opposite sides with a pair of bayonet grooves 6. A rotor 7, having 50 an annular flange 7' and an inturned end portion 8 is slidably mounted on the sleeve

4, and is held against rotary movement with relation to the sleeve by the nibs 9, projecting from the inturned end 8 into the bayonet grooves 6.

Surrounding the sleeve and disposed between the shoulder 5 and the inturned end 8, is a coil spring 10, adapted to normally urge the rotor in one direction. The rotor 7 is provided with an annular insulating 60 ring 11, of fibre or other suitable material, in which is flushly mounted a contact plate 12, secured to the annular flange 7' by a screw 12'. A pin 13, projecting thru the slot 13' formed in one end of the sleeve 4, 65 serves to hold the same against rotation on the shaft, and a retaining washer 14, provided with an inturned flange engages the pin to retain the same, and binds the sleeve against the shoulder 3 by means of the nut 70 75 threaded on the end of the timer shaft.

From the foregoing, it will be observed, 75 that for the purpose of removing the rotor to renew the same or any of its parts, the operation is comparatively simple, merely requiring the removal of the nut and washer, which allows the rotor to be withdrawn from the bayonet grooves 6. In the normal operation of the timer, the rotor is so positioned 80 on the sleeve that the nibs 9 engage the longitudinal stretches of the bayonet grooves. Hence the rotor is free to move longitudinally on the sleeve, and at the same time is held against rotary movement with 85 relation thereto.

A housing 16 is arranged concentrically 90 about the shaft and it is adapted to be oscillated upon its bearing (not shown), whereby the spark may be advanced or retarded. In the present form of housing illustrated in connection with the invention, 95 the same is provided with a plurality of binding posts 17, which have secured to their ends, interiorly of the housing, the closely coiled sections of spring 18, which have fitted thereon metallic heads 19 that form contact brushes, adapted to be engaged by the fibre ring 11 and the contact plate 12 carried thereby. The guides 20 secured to the housing by the binding posts 17 are provided with ears adapted to straddle the springs 18, to prevent the contacts from moving in a plane transverse to the axis of the timer shaft.

100 While I have shown and described a specific form of contact member which is yieldable in a plane parallel to the longitudinal

axis of the timer shaft, it will be understood that I do not claim the specific structure as part of the present invention, the same being disclosed in my previous application for patent filed July 26, 1921, Serial No. 407,653.

It will be also understood that while I prefer to employ a yieldable contact brush in connection with the present invention, I may, in some instances, substitute a rigid brush without departing therefrom.

It is a well known fact that in standard types of internal combustion engines, there is a great variation in the position of the timer shaft with relation to the housing or casing, and although the relative position of the two may be properly adjusted initially, the resultant wear upon the parts causes the members to shift, which results in either too slight a contact between the rotor and brushes or too great a contact causing undue wear upon both the brushes and rotor.

The present invention overcomes the foregoing disadvantages by mounting the rotor slidably longitudinally of the timer shaft and providing a spring to hold the rotor into engagement with the brushes. Thus as any shift or end play takes place between the timer shaft and housing carrying the contacts, the same will be compensated for by means of the yieldable connection between the rotor and timer shaft, thus maintaining a predetermined contact at all times which is regulated by a predetermined tension of the spring 10; it being appreciated that the slight retraction or expansion of the spring resulting from longitudinal shifting of the timer shaft will not materially effect the frictional engagement between the rotor and brushes.

I claim:

1. A timer comprising a housing, a plurality of contact members carried by the housing, a timer shaft positioned centrally

of the housing, a rotor comprising an annular fibre ring having a flush contact plate, said rotor being movable longitudinally on the shaft, and means for yieldably holding the rotor into engagement with the contact members.

2. A timer comprising a housing, a timer shaft positioned centrally of the housing, a plurality of contact members carried by the housing, said members being yieldable in a plane parallel to the axis of the timer shaft, a rotor comprising an annular fibre ring having a flush contact plate secured thereto, said rotor being movable longitudinally on the shaft, and means for yieldably holding the rotor into engagement with the contact members.

3. A timer comprising a housing, a plurality of contact members carried by the housing, a timer shaft positioned centrally of the housing, a sleeve secured on the timer shaft and provided with a bayonet groove, a rotor slidably mounted on said sleeve and provided with a nib engaging said bayonet groove, and yieldable means for holding the rotor into engagement with the contact members.

4. A timer comprising a housing, a plurality of contact members carried by the housing, a timer shaft positioned centrally of the housing, a sleeve secured on the timer shaft and provided with a bayonet groove, a rotor slidably mounted on said sleeve, a nib carried by the rotor for engaging said bayonet groove, an annular fibre ring carried by the rotor, a contact plate mounted in said fibre ring, and a spring disposed between the sleeve and rotor for holding the latter into engagement with the contact members.

In testimony that I claim the foregoing I have hereunto set my hand at Milwaukee, in the county of Milwaukee and State of Wisconsin.

ADAM W. KAUFMAN.
